UNITED STATES PATENT OFFICE.

CARL HASSSLER, OF AALEN, GERMANY.

ATOMIZER.

1,077,708.

Specification of Letters Patent.

Patented Nov. 4, 1913.

Application filed February 24, 1913. Serial No. 750,140.

To all whom it may concern:

Be it known that I, CARL HASSSLER, a subject of the King of Wurttemberg, residing at Aalen, Germany, have invented an Improvement in Atomizers, of which the following is a specification.

My present invention relates to an atomizer particularly adapted for liquids such as oils and like materials when the apparatus is used as a carbureter, but as will be understood, the apparatus may be used for atomizing any substance in a liquid form.

The objects of my present invention are to provide an atomizer in which the flow of the liquid to be atomized and consequently the supply of the same, is regulated and controlled by the air supplied to the apparatus and by which the liquid is atomized, and also to subdivide the air currents so that the mixture of the air and liquid will be as complete as possible.

In carrying out my invention, I employ a casing in which a discharge nozzle having a mixing chamber is fixed, and a discharge pipe for the liquid to be atomized extending into the mixing chamber and adjustable longitudinally to position therein, so as to vary the area of the air inlet to the mixing chamber to make the same equal to the area of the orifice of the discharge nozzle or greater than the same in order that the air in passing into and through the mixing chamber when the area of the air inlet is equal to the area of the mixing chamber nozzle, may create a suction or partial vacuum to assist in drawing the liquid from its supply pipe, or when in other positions, when the area of the air inlet is greater than the area of the mixing chamber orifice, there will be an accumulation of air in the mixing chamber under greater or less pressure, which will act to retard the flow of the liquid and hence control the same by regulating the air pressure in the mixing chamber. I also preferably employ partition walls forming a chamber into which a mixture of air and liquid is discharged so that the liquid is further mixed with additional quantities of air to insure a thorough mixing of the same.

In the drawing, Figure 1 is a central longitudinal section of an atomizer illustrating my present invention. Fig. 2 is a cross section on line A—B, Fig. 1. Fig. 3 is a view similar to Fig. 1, showing the parts in a different position. Figs. 4 and 5 are a longi-

tudinal section and transverse section respectively, showing a modified form of the invention, and Figs. 6 and 7 are views similar respectively to Figs. 4 and 5, showing a further modification of the invention.

Referring to the drawings and particularly to Figs. 1 to 3 inclusive, my improved atomizer comprises a casing indicated at *a* and provided with an air inlet *z* and a mixture outlet *x*. Within the casing *a* I preferably provide air passages indicated at *b* and *b'*, and suitably secured within the casing adjacent the mixture outlet *x* is a discharge nozzle *d* providing a mixing chamber *d'*, the walls of which are preferably made flaring as the same recede from the orifice of the nozzle. Extending into the mixing chamber *d'* is a liquid discharge nozzle *c*. This is connected to the end of a supply pipe *n* in any suitable manner and the supply pipe *n* is provided with a lug *m* in which is revolvably mounted a screw *m* engaging with a portion of the casing *a* so that by turning the screw *m*, the supply pipe *n* may be adjusted to determine the position of the end of the nozzle *c* within the mixing chamber *d'*. A portion of the air admitted at *z* will flow by way of the passage *b* to the mixing chamber *d'* entering the same by flowing around the nozzle *c*, that portion of the inlet chamber between the nozzle *c* and the adjacent walls of the chamber forming an air inlet for the same.

The apparatus is so constructed that when in its innermost position as shown in Fig. 1, the end of the nozzle *c* is of such a diameter that the area of the air inlet between the same and the adjacent walls of the mixing chamber is equal to the area of the orifice of the mixture discharge nozzle, so that in this position, the air may flow from the mixing chamber with the same velocity that it enters the same, and consequently will exert a suction action within the bore of the nozzle *c* which tends to accelerate the flow of the liquid from the supply pipe *n* whereas when the pipe *n* is adjusted to other positions, the area of the air inlet to the mixing chamber is greater than the area of the orifice of the mixing chamber nozzle, so that the air may be admitted to the mixing chamber with a greater velocity than it can escape therefrom. This will create an accumulation of air in the mixing chamber under greater or less pressure, which as will be understood, ex-

tends into the bore of the nozzle *c* and hence retards the flow of the liquid through the pipe *n*, and as will be further understood, the position of the nozzle *c* may be so adjusted as to regulate this air pressure to control the flow of the liquid through the supply pipe.

Within the passage *b'* I employ a valve *g* adapted to seat against a shoulder formed by a restricted portion of the passage adjacent the mixture outlet *x*. This valve *g* is provided with a tubular extension concentric with the passage *b'*, and in suitably spaced positions the valve is provided exteriorly with ribs *g'* which are of sufficient extent to contact with the inner face of that portion of the casing *a* in which the passage *b'* is provided. Within the valve *g* and extending therefrom is a tube *e*, and within the tube *e* is an auxiliary tube *f* concentric therewith and secured in position by means of the ribs *f'*. The discharge nozzle *d* from the mixing chamber, as clearly indicated in these figures, extends at an inclination through the walls of the tubes *e* and *f*, and the orifice thereof lies within the tube *e*, the pipe *n* with its nozzle *c* being in alignment with the mixing chamber nozzle *d*. The valve *g* may be moved to and from its seat by means of a revoluble member *h* passing through a sleeve *i* secured in the casing *a*, the revoluble member *h* having secured thereto exteriorly of the sleeve, a hand wheel *k* which may be locked in position by a set screw *l*, and within the casing and at the inner end of the revoluble member, the same is provided with a disk *r* having an eccentric pin *o* adapted to enter a slot *p* provided therefor in a lug *t* on one side of the valve *g*, so that the valve may be moved to position against its seat, as shown in Fig. 1, or to position from its seat as shown in Fig. 3, or may be placed in any position intermediate, by which as will be understood, the flow of air through the passage *b* may be further regulated and controlled.

It will be noted that when the valve *g* is closed, there are three passages through the atomizer, namely,—one through the passage *b*, one through the tube *f* and another through the annular space between the tubes *e* and *f*, all of which are reunited adjacent the mixture discharge *x* so as to insure a thorough mixing of the liquid and air, and that when the valve *g* is opened, there will be a fourth passage exteriorly of the same and the tube *e*.

Referring to Figs. 4 and 5, the discharge orifice of the mixing chamber nozzle is preferably formed with an angular incision indicated at *d²* so that the mixture of liquid and air will pass from the same in an angular form, and as shown in Figs. 6 and 7, the discharge nozzle of the mixing chamber

may be stepped as indicated at *d³* in Fig. 7, so that the mixture of air and liquid will pass from the same in this form in both cases, causing a more thorough additional mixture with the air which passes through the bore of the valve *g*, and which may pass around the valve exteriorly thereof.

I claim as my invention:

1. In an atomizer, the combination with a casing, a liquid nozzle adjustably mounted therein, a mixing nozzle mounted in front of the liquid nozzle, the area of the orifice of the mixing nozzle being equal to the area of the inlet for the supply of air when the liquid nozzle is nearest the mixing nozzle while the area of the air inlet in all other positions of the liquid nozzle is greater than the area of the orifice of the mixing nozzle, an additional air supply conduit arranged in the casing at an inclination to the axis of the liquid nozzle, into which conduit the mixing nozzle projects, the orifice of the mixing nozzle being so formed that the mixture of air and liquid flows therefrom in bands or ribbons transversely of the current of air in the said conduit, and means for regulating the flow of air through the said conduit.

2. In an atomizer, the combination of a casing, a liquid nozzle adjustably mounted therein, a mixing nozzle arranged in front of the liquid nozzle, the area of the orifice of the mixing nozzle being equal to the area of the inlet for the supply of air when the liquid nozzle is nearest the mixing nozzle, while the area of the air inlet in all the other positions of the liquid nozzle is greater than the area of the orifice of the mixing nozzle, an additional air-supply conduit arranged in the casing at an inclination to the axis of the liquid nozzle, into which conduit the mixing nozzle projects, and means for varying the flow of air through the additional air supply conduit independently of the inlet to the liquid nozzle whereby the regulation of the supply of liquid as well as the mixing action of air and sprayed liquid are increased.

3. In an atomizer, the combination of a casing, a liquid nozzle adjustably mounted therein, a mixing nozzle arranged in front of the liquid nozzle, the area of the orifice of the mixing nozzle being equal to the area of the inlet for the supply of air when the liquid nozzle is nearest the mixing nozzle, while the area of the air inlet in all the other positions of the liquid nozzle is greater than the area of the orifice of the mixing nozzle, an additional regulatable air supply conduit arranged in the casing at an inclination to the axis of the liquid nozzle, into which conduit the mixing nozzle projects, the orifice of the mixing nozzle being formed step-shaped, so that the mixture of air and

Liquid flows away at various elevations in the form of bands or ribbons transversely of the current of air in said conduit.

4. An atomizer comprising a casing providing separate air passages therein, a nozzle in which there is a mixing chamber the walls of which diverge as they extend from the discharge end of the said nozzle, an adjustable liquid supply pipe extending into the mixing chamber and providing an annular air inlet between its end and the diverging walls of the mixing chamber for air from one of the said passages, the area of the air inlet being equal to the area of the orifice of the nozzle when the pipe is in its innermost position, and larger than the area of the orifice of the nozzle when the pipe is in all other positions, means for adjusting the said liquid supply pipe in position within the said mixing chamber, and devices in the other air passage and independent of the mixing chamber for subdividing the air into a plurality of currents.

5. An atomizer comprising a casing providing air passages therein, a nozzle in which there is a mixing chamber the walls of which diverge as they extend from the

discharge end of the said nozzle, an adjustable liquid supply pipe extending into the mixing chamber and providing an annular air inlet between its end and the diverging walls of the mixing chamber for air from one of the said passages, the area of the air inlet being equal to the area of the orifice of the nozzle when the pipe is in its innermost position, and larger than the area of the orifice of the nozzle when the pipe is in all other positions, means for adjusting the said liquid supply pipe in position within the said mixing chamber, a valve in the second air passage, means for opening and closing the valve to vary the flow of air through both passages, and concentric tubes also within the second air passage and into the inner of which tubes the said discharge nozzle extends and its orifice is located.

In testimony whereof I have signed my name to this specification in the presence of two subscribing witnesses.

CARL HASSLER.
